(57) **CLAIM**

The ornamental design for a control element, as shown and described.

DESCRIPTION

FIG. 1 is a front elevational view of a control element showing my new design;

FIG. 2 is rear elevational view thereof;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a front left side perspective view thereof.

The broken line portion of the figure drawings is included to show unclaimed subject matter only and forms no part of the claimed design
